UNITED STATES PATENT OFFICE

CLAUDE HERBERT BRIGHT, JR., OF MEMPHIS, TENNESSEE

INKING PAD

Application filed August 13, 1929. Serial No. 385,667.

The invention forming the subject matter of this application is an inking pad of novel construction provided with means to control the moisture content of the pad by bringing the wick and pad into contact with each other as desired and to prevent oversaturation of the said pad, and for holding the pad out of contact with the contents of a reservoir after proper saturation of the pad while the pad is actually in use, so the re-inking process can take place without interrupting the use of the pad while the pad is being continuously or intermittently used.

The main object of the invention is to provide a device of this kind which shall be capable of prolonged use without replenishing the supply of ink for a great length of time.

Another object of the invention is to provide a device of this character which can be very cheaply manufactured and assembled, and, therefore, sold at very low cost.

Other objects of the invention will become apparent as the detailed description thereof proceeds.

In the drawings:

Fig. 1 is a perspective of the inking pad shown with the parts thereof in position for use, and with the inked element in position to absorb ink from a reservoir arranged below the said element;

Fig. 2 is a fragmentary vertical cross-section taken on the line 2—2 of Fig. 1;

Fig. 3 is a view similar to Fig. 2, but with the parts of the device in a different position;

Fig. 4 is a vertical transverse section taken on the line 4—4 of Fig. 3;

Fig. 5 is a vertical transverse section similar to Fig. 3, but illustrating the parts in closed position and having a cover extended over the inking pad to protect the latter;

Fig. 6 is a rear end elevation of the invention with the several parts thereof shown in closed position;

Fig. 7 is an end elevation of the invention with the several covers or lids thereof shown in open position;

Fig. 8 is an exploded perspective of the inking pad forming an essential part of this invention; and

Fig. 9 is a perspective of an inking pad illustrating the means for feeding ink from a reservoir to the parts of a wick which extend through one face of the pad.

The invention comprises a rectangular box 55 adapted to receive and retain a supply of stamping ink. A wick holding member fits slidably and snugly within the box 1 and has flanges 2, 3, 4 and 5 extending perpendicularly from the edges of its face 6 (see Fig. 9). 60 The lower edges of these flanges are coplanar and are adapted to rest upon the bottom 7 of the box 1 in order to support the face 6 at a predetermined distance below the upper edge 8 of the box 1. 65

The center of the face 6 is provided with a slot 9, in which a casing 10 fits with tight friction fit and with its upper edge substantially flush with the top of the face 6 (see Fig. 4). The casing 10 has brackets 11 and 12 secured to the opposite sides thereof and these brackets are integral with flanges 13 and 14, suitably secured to the lower side of the face plate 6. 70

The bottom edge of the casing 10 is raised 75 slightly above the bottom edge of the flanges 2, 3, 4, and 5 in order to permit ink to circulate freely in the chamber formed by the box 1. At the lower part of the casing 10, there is inserted a rectangular block 15 of felt, which 80 is adapted to suck ink from the interior of the box 1 by capillary attraction and feed it to a wick 16 formed of a rectangular piece of fabric of the same width as the width of the casing 10. 85

The wick 16 is secured in the casing 10 and in contact with the block 15 by means of an insert 17 of fiber or any other suitable material which forms a plug to hold the central loop of the wick 16 by friction against the inside of the side walls of casing 10. The wick 16 is long enough, after being secured in contact against the felt block 15 by means of the insert 17, to provide oppositely extending flaps 18 and 19 which are adapted to lie flat on the face plate 6 in order to make contact with a covering 20 of ink absorbent fabric secured to opposite faces of the pad 21. 95

In order to provide for expansion of the air 104 due to changes of temperature, and to pre-

vent the air pressure from forcing an over-supply of ink up through the wick, I have provided the face plate 6 with apertures 22 and 23 extending through the flanges 13 and 14 and registering with corresponding apertures 24 and 25 formed in the flaps 18 and 19 of the wick.

In order to provide a filling opening for the box 1, the end 26 thereof is provided with 10 an aperture 27, screwthreaded to receive the shank 28 of a thumb screw 29. The flange 4 is provided with an aperture 30, adapted to register with the aperture 27 for the purpose of locking the wick holding member in position in the box 1.

As previously described, the face plate 6 is located below the plane of the upper edge 8 of the box 1, and the space formed by the face plate 6 and the projecting side and end walls 20 of the box 1 is designed to receive, with snug fit, the pad 21 when located in position on the flaps 18 and 19 to have its covering 20 provided with the necessary amount of ink from the flaps 18 and 19. The pad 21 comprises 25 a rectangular plate, which may be hollow as shown in Fig. 4, having a rectangular groove 31 at one end thereof. A clamping plate fits slidably in this groove 31; and this clamping plate 32 is provided with an aperture 33, 30 through which passes freely the screw-threaded shank 34 of a thumb nut 35, which is provided with a shoulder 36, adapted to engage said clamping plate 32 and force it into clamping contact against the inner wall 35 of the groove 31. The inking fabric 20 is made of the same width as the width of the pad 21, and has the ends thereof brought together and inserted in the groove 31 to be clamped by the plate 32 in said groove so as 40 to stretch the fabric 20 tightly over the opposed faces of the pad 21.

The thumb nut 35 extends beyond the end wall of the box 1, which has the projecting portion thereof provided with an arcuate 45 notch 37, adapted to receive the cylindrical shank 38 of the thumb nut 35. By means of the thumb nut or screw 35, the pad 21 may be lifted from its supported position on the face plate 6 over the inking flaps 18 and 19, 50 and may be removed from the box 1 or reversed, for inking purposes, on the face plate 6 and in contact with the flaps 18 and 19.

If the pad 21 were left constantly in contact with the inking flaps 18 and 19, it would become 55 too moist for stamping purposes; therefore, it is necessary to provide some means for separating it from the inking flaps after it becomes properly saturated with ink, and for such length of time as it retains its state 60 of proper saturation. To effect this separation of the pad 21 from the inking flaps 18 and 19, the rear end of the box 1 is provided 65 with a hinged plate 39, which fits snugly into the space formed by the projecting parts of the walls of the box 1 above the face plate 6.

A hinge 40 has one of its leaves fixed to the rear walls of the box 1, and has its other leaf 44 suitably fixed to the inner face of the plate 39.

The inner face of the plate 39 has a pad of 70 leather or any other suitable material fixed thereto; and the central part of this pad 41 is cut out to form a rectangular recess 42, slightly larger than the spread out area of the flaps 18 and 19. The pad 41 is also cut 75 away to form a groove 43 in which is received the leaf 44 of the hinge above referred to.

The rear wall of the box 1 is provided with a notch 45, through which the leaf 44 of the said hinge is adapted to swing for the purpose of permitting the plate 39, with its pad 41, to rest upon the face plate 6, and to cover the flaps 18 and 19, while remaining out of actual contact with said flaps. When in this position, the properly inked pad 21 is intended to be seated on the plain back face of the plate 39. The plate 39 is provided with a lug 46 projecting from the center of the front edge of said plate; and this lug is adapted to seat in a notch 47, formed in the 90 upper edge of the front wall of the box 1, where it projects above the face plate 6. This lug 46 is provided merely to enable the operator to move the plate 39 to and from the position shown in Fig. 3 of the drawings. 95

A cover 48 is also hinged to the rear wall of the box 1 and is adapted to be swung to open position in advance of and under the separator plate 39; and to be swung to closed position as shown in Fig. 3, only after the 100 plate 39 shall have been moved to its operative position on the face plate 6.

In the operation of the invention, assuming that the reservoir has been properly filled and the wick supporting part of the invention has been securely locked by the thumb screw 29 in said reservoir, it is evident that if the pad 21 be placed directly on the inking flaps 18 and 19, as shown in Fig. 4, it will absorb ink from the said flaps drawn by 110 capillary attraction from the block 15 in contact with the ink in said reservoir.

The double faced pad 21 absorbs ink from the wick sufficient to ink the pad with the desired degree of moisture in about fifty or sixty seconds. When it is properly inked, it may be lifted from the ink absorbing position by the thumb screw 35. Then the separator plate 39 is swung from its open position to cover the inking flaps 18 and 19. The inked pad 21 may then be placed on top of this cover ready for use. The hinge cover 48 may then be swung over the top of this inking pad 21 to protect it from dust and to prevent or retard evaporation of ink therefrom when not in actual use.

What I claim is:

1. An inking appliance comprising a box, a supporting plate having a slot through the center thereof and having flanges depending 130

from the outer edges thereof to seat on the bottom of said box, means engaging one end of said box and one of said flanges to lock said plate in position in said box, a casing 5 depending from said plate and surrounding said slot, means for securing said casing to said plate, a wick comprising a sheet of ink absorbing fabric mounted in said casing and having flaps lying on the face of said plate 10 on the opposite side of said slot, a pad adapted to seat on said plate, and means hinged to said box for separating and supporting said pad from said plate.

2. A reservoir adapted to contain ink, a 15 plate supported in said reservoir below the top thereof, means for feeding ink from said reservoir to the top of said plate, a reversible pad supported by said plate, and means carried by said reservoir and adapted to be 20 moved into supported contact with said plate to prevent access of ink from said reservoir to said pad.

3. A reservoir adapted to contain ink, a 25 plate provided with a slot, means for supporting said plate in said reservoir, means for locking said plate in supported position in said reservoir, a casing depending from said plate and having its upper end fitting said slot, said casing terminating slightly above 30 the bottom of said reservoir, a block of felt secured in said casing and projecting therefrom into said reservoir, a wick comprising a sheet of fabric bent to form a loop having the bend thereof in contact with said block of 35 felt and having the opposite ends thereof bent to form flaps lying on top of said plate on opposite sides of said slot, and means for securing said wick in said casing and in contact with said block of felt.

40 4. A reservoir adapted to contain ink, a pad supporting plate fitting snugly and slidably in said reservoir, means for locking said plate in fixed position in said reservoir, means for conducting ink from said reservoir to the 45 top of said plate, a pad adapted to be supported on said plate, and means secured to said plate and movable relative thereto to support said pad on said plate but out of contact therewith.

50 5. An inking appliance comprising a box having a filling aperture through one end thereof, a thumb screw for closing said aperture, a pad supporting plate mounted in said box bellow the top thereof and having a 55 flange depending therefrom, said flange being provided with an aperture registerable with the first named aperture and adapted to be engaged with said thumb screw to lock the plate in position in said box, means for 60 feeding ink from said reservoir to the upper face of said plate, a reversible pad supported on said plate, and a separator plate hinged to the back of said box and adapted to contact with and be supported by said supporting plate.

6. An ink pad comprising a container, a hinged lid for the container, a pad adapted to seat in both the lid and the container, a plate positioned in the container below the top thereof, means for feeding ink from the 70 container to the top of the plate, a second plate hingedly mounted on the container and adapted to seat over the plate, whereby the pad when positioned in the lid is always separated from the plate. 75

In testimony whereof I affix my signature.
